CARD INDEX

Raymond E. Bauder, Chicago, Ill.

Application March 18, 1943, Serial No. 479,653

13 Claims. (Cl. 129—16.7)

In card index systems, particularly those in which a plurality of superposed cards are hooked one upon another in a tray, it is often desirable to readily attach an auxiliary card or a small card constituting a conspicuous marker, to any of the main cards, to which attention must be drawn at some later time, and it is the object of the present invention to make novel provision whereby any such auxiliary card may be quickly and easily attached to or detached from a main card without the necessity of removing the latter from the tray.

A further object of the invention is to provide a novel construction which is exceptionally simple and inexpensive and may be expeditiously manufactured, yet one which will be durable and desirable from all standpoints.

With the foregoing in view, the invention resides in the novel subject matter hereinafter described and claimed, description being accomplished by reference to the accompanying drawings.

Figure 1 is a front elevation showing an auxiliary card attached in accordance with the present invention to a main card.

Fig. 2 is an enlarged fragmentary sectional view on line 2—2 of Fig. 1.

Fig. 3 is a fragmentary longitudinal sectional view on line 3—3 of Fig. 2.

Fig. 4 is a perspective view partly broken away and in section showing the first step necessary in removing a relatively large auxiliary card from the main card.

Fig. 5 is a view similar to Fig. 4 showing the manner in which a second removal step for the auxiliary card, is performed.

Fig. 6 is a view similar to Fig. 1 but illustrating a comparatively small or marker card attached to the main card in accordance with the invention.

Fig. 7 is an enlarged detail sectional view on line 7—7 of Fig. 6.

Figs. 8 and 9 are fragmentary perspective views, partly in section, showing certain steps which are performed in removing the auxiliary or marker card from the main card.

Preferred features of construction have been illustrated and will be specifically described, with the understanding, however, that within the scope of the invention as claimed, variations may be made.

A main card 10 is shown of the general form disclosed in my pending U. S. application Serial No. 475,119, filed February 8, 1943, since matured into Patent No. 2,341,522, dated February 15,

1944, said main card having a folded-over head bar 11 overlying its upper edge portion, said head bar and subjacent portion of the card projecting from the major portion of the card to provide ears 12 for slidable reception in guide grooves of a filing tray (not shown). Tongues 13 are formed integrally with the lower edge of the head bar 11, as in the application above referred to, said tongues extending rearwardly through slots or slits 13a in the card 10 and diverging downwardly from said card 10 to hook over the upper or head bar portion of a subjacent card. While I have shown two of the tongues 13 and two slots 13a receiving said tongues, there could obviously be more or less than two. To obviate, however, indulging too much in generalities, the descriptive matter will be confined to the two-tongue and two-slot construction shown.

In the form of construction illustrated in Figs. 20 to 5, inclusive, 14 denotes a relatively large auxiliary card lying against the front or upper side of the main card 10, said auxiliary card having upper edges 15 in abutting relation with the portions of the tongues 13 which extend from the head bar 11 to the slots 13a. The upper end of the card 14 is provided, in the present disclosure, with three flanges 16, 17 and 18 which project beyond the edges 15 and are received between the main card 10 and the head bar 11, 25 said flanges embracing the portions of the tongues 13 which extend between said head bar and card 10 and thus securing the auxiliary card 14 to the main card. The flange 16 and the flange 17 jointly embrace one of the tongues 13 and are provided with integral lugs 19 which project inwardly toward each other and hook behind the portion of said tongue which extends from the head bar 11 to the slot 13a receiving said tongue. The two flanges 17 and 18 30 jointly embrace the other of the tongues 13, and said flange 18 is provided with an integral lug 20 extending toward the flange 17 and hooked behind the portion of said other of said tongues which extends from the head bar 11 to the subjacent slot 13a. While the central flange 17 is 35 preferably employed, it obviously might be omitted, leaving the auxiliary card 14 attached to the main card 10 by means of the other two flanges 16 and 17 embracing the tongues 13. 40 All of the flanges 16, 17 and 18 and the auxiliary card 14 lie in the same plane, and are provided with hinge portions joining said flanges to said auxiliary card (preferably integrally) along alined hinge lines 21 which permit said auxiliary card 14 to be swung upwardly into a plane per-

pendicular to the main card 10. By grasping the right and left end portions of card 14 with the right and left hands, when said card is swung to perpendicular position, the end portions of said card, carrying the flanges 16 and 18, may be relatively angled as shown in Fig. 4, thus so spreading said flanges 16 and 18 as to permit release of these flanges from their embracing relation with the tongues 13. This having been done, the card 14 may be shifted substantially to the position shown in Fig. 5 and slid endwise to disengage the lug 19 of flange 17 from the tongue 13 which it previously engaged. A reversal of these operations is employed when attaching the auxiliary card 14 to the main card 10.

In Figs. 6 to 9, a relatively small auxiliary card or marker card 14^a is shown lying directly upon the main card 10, but it could of course lie upon one of the auxiliary cards 14 above described. In either instance, the card 14^a is attached to the main card 10 in the same general way as said card 14 is attached.

In the present showing, the card 14^a is of substantially T-shape, the ends of the T-head being indicated at 22. This specific shape for the card, however, is not essential. The card 14^a is provided with an upper edge 15^a in abutting relation with the portion of one of the tongues 13 which extends from the head bar 11 to the subjacent slot 13^a, and said card is provided also with flanges 16^a and 18^a projecting beyond said edge 15^a, said flanges having integral lugs 19^a and 20^a which hook behind the portions of the tongue embraced by the flanges. These flanges are preferably integral with the card 14^a and said card and flanges are provided with hinge portions joining said flanges to said card (preferably integrally) along hinge lines 21^a which permit the body portion of the card 14^a to be upwardly swung into a plane perpendicular to the main card 10, as shown in Fig. 8. With the card in this position, its flange-carrying portions may be relatively angled to permit disengagement of the flanges 16^a and 18^a from the tongue 13. It is preferable to spring back the end 22 of the T-head carrying the flange 18^a, with the tip of the forefinger and thumb, thus moving said flange 18^a to the tongue-clearing position shown in Fig. 8. The card 14^a may then be sprung a little to permit the lug 20^a to entirely clear the tongue 13 as seen in Fig. 9, whereupon said card may be slid to unhook the lug 19^a of the flange 16^a from said tongue 13. To facilitate such removal of the card 14^a from the main card 10, as well as application of said card 14^a to the main card, it is preferable to provide the T-head ends 22 and the body portion of the card, with hinge portions joining said T-head ends 22 and said body portion of said card along hinge lines 23.

From the foregoing taken in connection with the accompanying drawings, it will be seen that novel and advantageous provision has been made for carrying out the objects of the invention. While preferred details of construction have been illustrated, attention is again invited to the possibility of making variations within the scope of the invention as claimed. Moreover, it will be obvious that while the invention is intended primarily for connecting an auxiliary card to a main card of a card index, it is not restricted to this particular field, in which connection it will be clear that the main card 10, in a broad sense constitutes a mere support or carrier for the auxiliary card 14 or 14^a, and that the tongues 13 form card anchoring means which could take

other form, and that other provision could well take the place of the head bar 11 to prevent mere lifting of the auxiliary card from the card anchoring means. Moreover, it is to be understood that the word "card" does not necessarily mean a stiff card nor one of any particular thickness, mere paper thickness being often adequate.

I claim:

10. An assemblage of the class described comprising a card support having a flat card-supporting side, card-anchoring means projecting from said card-supporting side of said card support, a card lying upon said card-supporting side of said card support and having an edge disposed in abutting relation with said card-anchoring means, two spaced flanges projecting beyond said edge of said card, said flanges jointly embracing said card-anchoring means to secure said card to said support, said card and flanges being in the same plane and having hinge means joining said flanges to said card along alined hinge lines which permit said card to be swung into a plane perpendicular to said flanges, whereby the flange-carrying portions of said card may be relatively angled to spread said flanges from their embracing engagement with said card-anchoring means when said card is swung into said plane, and means connected with said card support and overlying said card to hold the latter upon said card support.
20. A structure as specified in claim 1; said flanges having lugs projecting toward each other and hooked behind said card-anchoring means.
25. 3. A structure as specified in claim 1; said card-anchoring means being a single member embraced by said flanges.
30. 4. A structure as specified in claim 1; said card-anchoring means being a single member embraced by said flanges, one of said flanges having a lug projecting toward the other flange and hooked behind said member.
35. 5. A structure as specified in claim 1; said card-anchoring means being a single member embraced by said flanges, said flanges having lugs projecting toward each other and hooked behind said member.
40. 6. An assemblage of the class described comprising a flat card support, a bar overlying the upper portion of said support, and tongue means extending from said bar to said support; a card overlying said support and having an upper edge in abutting relation with said tongue means, two spaced flanges joined to said card and projecting beyond said upper edge thereof, said flanges lying between said support and said bar and jointly embracing said tongue means, said card and flanges having hinge means joining said flanges to said card along alined hinge lines which permit said card to be swung into a plane perpendicular to said flanges, whereby the flange-carrying portions of said card may be relatively angled to spread said flanges from their embracing engagement with said tongue means for removal of said card when the latter is swung into said plane.
45. 7. A structure as specified in claim 6; said flanges having lugs projecting toward each other and hooked behind said tongue means.
50. 8. A structure as specified in claim 6; said tongue means being a single tongue embraced by said flanges.
55. 9. A structure as specified in claim 6; said tongue means being a single tongue embraced by said flanges, one of said flanges having a lug

projecting toward the other flange and hooked behind said tongue.

10. A structure as specified in claim 6; said tongue means being a single tongue embraced by said flanges, said flanges having lugs projecting toward each other and hooked behind said tongue.

11. A structure as specified in claim 6; said tongue means comprising two tongues spaced apart, said two flanges having lugs projecting toward each other and hooked behind the outer edge portions of said two tongues respectively, and a third flange connected with said card and extending between said two tongues, said third flange being confined between said support and said bar and having a single lug hooked behind the inner edge portion of one of said tongues, said third flange and said card having hinge means joining said third flange to said card along a hinge line alined with those aforesaid.

12. A card for connection with anchoring means, said card having an edge for abutting relation with the anchoring means and having two flanges projecting beyond said edge to embrace the anchoring means, said card and flanges being in the same plane and having hinge means joining said flanges and card along alined hinge lines which permit swinging of said card into a plane perpendicular to said flanges, whereby the 10 flange-carrying portions of said card may be relatively angled to spread said flanges for engagement with the card-anchoring means, when said card is swung into said plane.

13. A structure as specified in claim 12; said 15 flanges having lugs projecting toward each other to hook behind the anchoring means.

RAYMOND E. BAUDER.
